CLOSURE DEVICE

Ralph W. De Lancey, Meriden, Conn.

Application May 2, 1945, Serial No. 591,564

2 Claims. (Cl. 220—25)

1

The present invention relates to closure devices.

Steel drums, barrels, tanks, and the like, used for storage and transportation of petroleum products and many other purposes are frequently provided with threaded bushings to receive closures which are threaded into the bushings. Many of these closures in common use require special tools for the removal of the closure, and hence access to the contents of the drum may be very difficult or impossible because the proper tool is not available, and in opening the drum by anything else than the proper tool destruction or impairment of the closure is likely to occur.

The present invention relates to closures more suitable for use with such drums, as well as for carrying of accessory devices such as depth gauges, and requiring no special tools other than an ordinary screw driver or similar instrument to remove or replace the closure.

The present invention contemplates that the closure device instead of being threaded into the bushing is one which can be used either with the threaded bushing or with drums having openings which are not threaded. The closure device is provided with two or more L-shaped, or angle, pieces. Their lower ends can either be positioned so that they underlie the material of the drum or the like, or they may be swung or shifted from such underlying position to an interior position where they will not interfere with the removal or replacement of the closure.

According to the present invention these angle members may be tightened in place or released by nuts threaded on them and capable of being turned by means of a screw driver or similar device.

The accompanying drawings show, for purposes of illustrating the present invention, three embodiments in which the invention may take form, together with a depth gauge carried by such a closure, it being understood that the drawings are illustrative of the invention rather than limiting the same.

In these drawings:

Figure 1 is a transverse sectional view through a closure device and conventional threaded closure taken on the line 1—1 of Figure 3;

Figure 2 is a view of the closure device alone taken at right angles to Figure 1;

Figure 3 is a section of the closure device alone taken on the line 3—3 of Figure 1;

Figure 4 is a sectional view similar to Figure 1, but showing the angle member in release position;

2

Figure 5 is a view similar to Figure 4 illustrating a modified form of construction;

Figure 6 is a fragmentary elevational view taken in the direction of the arrow 6 of Figure 5;

Figure 7 illustrates a slightly modified form of closure with which is incorporated a depth gauge;

Figure 8 is a sectional view taken on the line 8—8 of Figure 7; and

Figure 9 is a diagrammatic view illustrating the assembly of the gauge of Figure 7 and the tank.

In the drawings a fragment of a steel drum, oil tank or the like, is illustrated at 10 and a conventional internally threaded bushing is shown at 11.

The closure device employs a plate 12 adapted to overlie the bushing. A gasket 13 will, of course, usually be employed.

The plate 12 is provided with two downwardly extending lugs 15, 15 preferably spaced to act as guides in one size of bushing. Adjacent each lug is a hole having a small diameter portion 16 and a large diameter portion 17 with an intermediate outwardly facing shoulder 18. An L-shaped angle clamping member 19 having a threaded shank portion 20 and a horizontal portion 21 extends up through the small diameter portion 16 of the hole. It is threaded into a nut 22 counterbored as indicated at 23, and its upper end is upset as indicated at 24 so that the nuts and angle member are inseparable. A gasket 25 is interposed between the bottom of the nut and the shoulder 18. The counterbore 26 is closed by a plug 26 having a forced fit, and a screw slot 27 extends across the top of the nut and the plug. The plug is short so as to provide space to accommodate the upper end of the angle member.

40 The angle member is made of such length that when the nut is unthreaded the lower end of the angle member will be substantially below the inner wall of the tank, as indicated in dotted lines in Figure 1, or in full lines in Figure 4.

45 The L-shaped member can be turned from the full line position of Figures 1, 2 and 3 to the dotted line position of Figure 3, or full line position of Figure 4, by turning the nut to the left, as in an unthreading operation, as far as it will go, by hand or by means of a screw driver. The angle member will then be in an inner position and passes down through the bushing 11. Now when one applies a screw driver to the nut and turns it to tighten the nut, the right hand turning of the nut will swing the angle member from the inside position to the outer position shown

50

55

in Figures 1 to 4, the lugs 15 being of such shape as to limit the swinging motion in each direction as will be obvious from Figure 3.

Continued turning of the nuts to tighten the threads will draw the angle members up against the inside wall of the drum or tank thereby effecting a very tight closure. The protruding central portion 14 of the cover plate receives the nuts so that they are protected against injury, and further protection may be afforded by gaskets 28 and a removable sheet metal channel 30 which can be snapped into position after the closure has been secured in position. This sheet metal cover can be readily removed by simply inserting a screw driver under the edge and prying it off.

In the modified form of construction illustrated in Figures 5 and 6 the closure device 31 is provided with two lugs 32 between which the angle member 33 is located. The lugs 32 are spaced to act as guides in a small bushing 34. The cover plate has a small seat 35a and a larger seat 35b to fit a larger bushing 34. The nut 36 is carried on the upper threaded end 37 of the angle members as before. When the parts are in the full line position of Figure 5 and the nut tightened the closure is clamped in place. When the nut is loosened the nut and L-shaped member can be swung as indicated in dotted lines, Figure 5. This freedom of movement may be had by various constructions giving sufficient looseness between the nut and the hole in the closure body which receives the nut. Such a space is indicated at 38.

The arrangement shown in Figure 7 employs a closure device similar to that shown in Figure 1; but as this device is not exposed to shipping hazards, the nuts 22 need no protection. The cover plate 40 is stepped, as indicated at 41 and 42, so that it can fit over different sized openings. The body member 40 is provided with a central opening 43 to receive a gauge rod 44. The body member 40 also carries a tube 45 and a cover 46 held on by screws 47. Suitable gaskets as at 48 and 49 make the device sufficiently tight to be used on top of an oil storage tank, a fragment of which is indicated at 10. The body member 40 carries a header rod 50 of such a length as to extend down to the center of the tank. A sheet metal arm 51 is pivoted at the lower end of the header and is provided with a number of holes such as indicated at 52, 53, 54 and 55. The lower end of the gauge rod 44 enters the hole 52. This rod is of the proper length that when the arm 51 is in a horizontal position the upper end of the gauge is at the halfway mark in the gauge tube 45. The holes 53, 54 and 55 are for the reception of the end of the float arm 56, this arm being of the proper length for the depth of tank used.

The assembly of the gauge in Figure 7 on the top of the tank is shown diagrammatically in Figure 9. Here the top wall of the tank is indicated at 10a, the bottom at 10b and the center line at 10c. When the instrument is outside the tank the parts can hang down vertically as indicated in Figure 9, and the float F can pass down through the opening in the tank. When it reaches the bottom of the tank or the oil in the tank it will shift laterally, as indicated in Figure 9, and permit passing the header and gauge rod down through the opening. The gauge can then be secured in position by tightening up the clamping members 19. The target on the gauge rod 44 will be at such an elevation that it will be opposite the proper place on the gauge glass.

When the tank is half filled the target will be moved up to the middle of the gauge glass and when the tank is full the target will be moved up to the "full" position.

5 With this device one can readily place the float arm in such a position as to have the float centralized laterally of the tank. A simple screw driver is all that is needed to attach a gauge to a tank.

10 The device may be readily adapted for use with tanks of various vertical depths by merely selecting the length of the head rod and the length of the stem 44 so that the pivot point will be at the center of the tank and the gauge target at "half full" when the float arm is horizontal, this arm being of sufficient length to permit the float to swing all the way from the bottom to the top of the tank:

Since it is obvious that the invention may be embodied in other forms and constructions within the scope of the claims, I wish it to be understood that the particular forms shown are but a few of these forms, and various modifications and changes being possible, I do not otherwise limit myself in any way with respect thereto.

What is claimed is:

1. In a closure, a cover plate adapted to overlie an opening, L-shaped members extending through holes in the plate and having lower ends spaced from the plate and shiftable from locking positions in which they extend outwardly to underlie the opening to released positions within the opening in which they do not interfere with removal or replacement of the closure, the plate having on its lower face a lug adjacent each L-shaped member, each lug having two faces forming a vertical dihedral angle within which said L-shaped member is disposed, the L-shaped members having threaded upper ends, and nuts 30 non-removably carried on said threaded ends, the nuts when tightened bearing on the upper face of the plate so that clamping pressure may be applied, the nuts when loosened freeing the members for movement to released position, the said faces of the lugs forming angularly spaced stops against which the lower ends of the L-shaped members are brought when tightening or loosening the nuts, the lengths of the lugs being such that the lower ends of the L-shaped members 35 when in their lowermost positions, engage the lugs.

2. A closure device for closing an opening in a tank and comprising a plate having an annular seat adapted to overlie the opening and having 55 holes inside the seat and at the bottom of upwardly opening recesses, L-shaped members threaded at their upper ends and having shank portions loosely extending through the holes in the plate and lower ends spaced below the plate

60 and positionable under the seat or inside the seat, cap nuts non-removably carried by and enclosing the threaded ends so that said ends are inaccessible, the cap nuts being provided with screw driver slots and received in the recesses so as to 65 be protected by the plate, said cap nuts being threaded at their lower ends to fit the threads so that the lower ends of the L-shaped members may be raised by tightening the nuts and lowered by loosening them, the plate having

70 downwardly extending lugs arranged about the lower ends of the L-shaped members and provided with faces which limit the turning of the respective L-shaped members in the holes in both directions, whereby when the nuts are tightened and 75 lower ends of the members project underneath the

seat the closure may be secured to the tank and when the lower ends of the members are inside the seat, the closure may be removed or replaced.
